UNITED STATES PATENT OFFICE.

FRANCIS LEE CASTLEMAN, OF PENCOYD, PENNSYLVANIA.

RAIL-FASTENING.

1,259,488.

Specification of Letters Patent. Patented Mar. 19, 1918.

Application filed November 8, 1917. Serial No. 200,943.

To all whom it may concern:

Be it known that I, FRANCIS LEE CASTLEMAN, a citizen of the United States, residing at Pencoyd, in the county of Montgomery and State of Pennsylvania, have invented certain new and useful Improvements in Rail-Fastenings, of which the following is a specification.

My invention relates to the construction of rail fastenings used in securing the track rails of a railway track, crane runway, or similar structure in place on the ties, stringers, or other support for the rails, and while not restricted to such use, the invention more particularly relates to the construction of rail fastenings employed in alining and securing the parallel track rails in alined position on the girders of a bridge or trestle.

One object of this invention is the provision of a rail fastening of improved construction and having novel means whereby the rails of a railway track are adjusted laterally to gage and into alinement and are securely held in adjusted position.

Another object of the invention is to provide a rail fastening having the novel constructions, combinations, and arrangement of parts, shown in the drawings, to be described in detail hereinafter, and to be particularly pointed out in the appended claims.

Referring now to the drawings, forming part of this specification, Figure 1 is a sectional elevation showing a rail fastening constructed and arranged in accordance with my invention, with the rail shown in one extreme adjusted position (to the left) relative to the tie plate or other rail support.

Fig. 2 is a sectional elevation similar to that of Fig. 1, showing the rail in the opposite extreme adjusted position (to the right) relative to the tie plate or rail support.

Fig. 3 is a plan, partly in section, of the apparatus shown in Figs. 1 and 2, the rail being shown in a position midway between that of Fig. 1 and that of Fig. 2 relative to the rail support.

Fig. 4 is a sectional elevation similar to those of Figs. 1 and 2, showing a modified form of rail fastening as constructed and arranged in accordance with my invention.

Figs. 5, 6, 7, 8, and 9, are sectional elevations similar to that of Fig. 4 showing other modified forms of rail fastenings embodying my invention.

In the accompanying drawings, the numeral 1 designates a track rail supported on a plate 2, which plate may be the rail engaging surface of a rail tie, a tie-plate, the top cover plate of a bridge girder or crane girder, or other rail supporting structure. The plate or rail support 2 is provided with circular openings 3, 3', which are located between the rail base or flanges and the outer edges of the plate 2, through which the fastening bolts 10, 10' extend.

In the construction shown in Figs. 1, 2, 3, and 4, and in the modified constructions shown in Figs. 4, and 5, an intermediate plate or filler 4, 4', is interposed between the plate 2 and the rail clips 6, 6', these filler plates having holes 5, 5' therein which register with the openings or holes 3, 3' in the plate 2. The thickness of the filler plates 4, 4', owing to the contacting surfaces of the rail flanges and rail clips being beveled, will depend upon the position of the holes 3, 3' in the plate 2 relative to the edges of the base or flanges of the rail 1.

In the fastenings shown in Figs. 6, 7, 8, and 9, the filler plates 4, 4' are omitted, these constructions also differing in other ways from that of Figs. 1, 2, and 3, and that of Fig. 4, as will be described hereinafter.

Pairs of rail clips 6, 6' are arranged on opposite sides of the rails 1 to adjustably secure the rails on the plate 2 or equivalent rail support, the adjacent ends of each pair of rail clips being beveled on the lower side thereof and engaging with the beveled upper surface of the rail base or flanges. Preferably, the rail clips will project into holding engagement with the web of the rail in the manner shown in full lines in Figs. 1 to 5. When found necessary or desirable, as for example with the smaller sizes of rails, the ends of the rail clips may terminate short of the web of the rails, in a manner similar to that shown in Figs. 6, 7, 8, or 9, so as to not contact with the rail web.

In the apparatus of Figs. 1, 2, and 3, and also in the constructions of Figs. 4 and 5, the rail clips 6, 6' have circular openings or holes 7, 7', the axes of these openings being out of alinement with the axes of the fas-

tening bolts 10, 10' which extend through the holes 3, 3' in the rail support 2; the holes 5, 5' in the filler plates 4, as well as through the holes 7, 7' in the rail clips in fastening the rail clips in adjusted position. The eccentric openings or holes 7, 7' in the rail clips are of larger diameter than the holes 3, 3' and 5, 5', and positioned in each of the eccentric openings 7, 7' is a circular washer 8 or 8'. Each of the washers 8, 8' has an axially eccentric opening 9 therein which is rectangular in outline, to receive the square shoulder 11, 11' on the bolts 10, 10' by which the eccentric washers 8, 8' are rotated in moving the rail clips to align or adjust the rails sidewise and by which the rail clips are held in adjusted position. Bearing plates 15, 15' are positioned on top of the rail clips 6, 6', in the construction of Figs. 1, 2, and 3, these plates being of a length substantially equal to that of the rail clip, as is shown in Fig. 3, and the plates 15, 15' have pairs of holes 16, 16' therein through which the bolts 11, 11' extend. The holes 16, 6', as is clearly shown in Fig. 3, are made large enough in diameter to permit the square portion 11, 11' of the bolts 10, 10' to rotate freely therein when the bolts are being turned, to adjust the rail clips and rail on the rail support 2. A separate plate may be provided for each bolt when desired, instead of one plate for each pair of bolts, as shown. The threaded ends 12, 12' of the bolts projecting through the rail support or plate 2, have nuts 13, 13' thereon, and, preferably, will be provided with locking washers 14, 14' or other suitable nut lock.

In the modified form of rail fastening shown in Fig. 4, an eccentric or cam surface 20, 20' is formed integrally on the bolts 10, 10' and the head of the bolts is made large enough to have a substantial bearing against the upper face of the rail clips 6, 6', the bearing plates 15, 15' being omitted.

In the modification shown in Fig. 5, the eccentric washers 8, 8' are flanged, so that the flanges bear against the upper surface of the clips 6, 6', the bearing plates 15, 15' being omitted in this construction also. In other respects the construction is the same as in Figs. 1, 2, and 3.

In the modified construction shown in Fig. 6, the holes 7, 7' in the rail clips 22, 22' are counterbored to form a rabbeted recess in which the eccentric washers 8, 8' are located, the bottom surface of the eccentric washers bearing against the bottom 23, 23' of the rabbet, and in this case the bearing plates 15, 15' and filler plates 4, 4' are omitted. The rail clips bear on one end on the rail support 2, and the other or beveled end of the clips bears on the beveled upper surface of the rail flange, a shoulder 24 on the rail clips engaging with the outer edge

of the rail flanges to hold the rails in adjusted position. The holes 7, 7' in the rail clips 22, 22' are made large enough to permit of the movement of the rail clips necessary in adjusting the rails by means of the eccentricities 8, the holes 7 being either circular or elongated, as is desired. In both cases the rabbeted recess in the clips 22, 22' will be circular.

In the further modified construction shown in Fig. 7, the filler plates 4, 4' are omitted and also the bearing plates 15, 15', the rail clips 26, 26' bearing at one end on the rail support 2, and having a bevel on the opposite end engaging with the beveled upper surface of the rail flanges, these rail clips also having a shoulder 27 engaging with the edges of the rail flanges in the same manner as in Fig. 6.

The holes 7, 7' in the rail clips 26, 26' are tapered, and the bolts 10, 10' extending through these holes have an integrally formed eccentric or cam surface 25 thereon which is seated in the tapering holes 7, 7'. In this construction the head of the bolt does not bear on the top surface of the rail clips, as in Fig. 4.

In the modification shown in Fig. 8, the heads 28, 28' of the bolts 10, 10' are made cylindrical and eccentric to the body of the bolts. A recess or transverse slot is provided in the upper surface of the eccentric heads 28, 28' for rotating the bolts. The rail clips 29, 29' bear at one end on the rail support 2, and have a beveled surface at the other end which engages with the beveled surface of the rail flanges, the shoulders 31, 31' on the rail clips engaging with the edges of the rail flanges in securing the rails in adjusted position. The upper surface of the rail clips 29, 29' has a shoulder 30, 30' which engages with the side of the eccentric heads 28, 28' on the bolts 10, 10' in adjusting the rail clips and rail and holding them in adjusted position.

In the modification shown in Fig. 9 the threaded ends 12, 12' of the bolts 10, 10' extend upwardly through the openings 3, 3' in the rail support 2, and openings 7, 7' in the rail clips 32, 32', the heads 36, 36' of the bolts engaging with the under surface of the rail support 2. The rail clips have rabbeted recesses therein to receive the eccentric washers 33, 33', and the openings or holes for the bolts 10, 10' in the washers 33, 33' are screw threaded, locking nuts 13, 13' also being provided on the threaded ends 12, 12' of the bolts. In adjusting the rails to alignment the under surfaces of the washers 33, 33' are kept out of contact with the bottom 35, 35' of the rabbeted recesses in the upper surface of the rail clips, and after the adjustment is made the eccentric washers 33, 33' are held against rotation by means of the nuts 13, 13' while the bolts are being

turned through the agency of the bolt heads 36, 36' to draw the eccentrics into tight engagement with the bottoms 35, 35' of the recesses in which the eccentrics 33, 33' are seated.

In applying my improved rail fastening shown in Figs. 1, 2, and 3, the parts will be assembled as shown. When adjusting the rail 1 sidewise into alinement or to gage, the 10 nuts 13, 13' will be slackened, and the bolts 10, 10' will then be turned by means of a wrench which is applied to the bolt heads. The bolts on one side of the rail will first be turned to loosen the rail clip on that side of 15 the rail, care being taken to rotate the bolts and eccentric washers turned thereby to substantially the same extent. The bolts on the opposite side of the rail will then be rotated to turn the eccentric washers on these bolts 20 and move the rail clips and rails sidewise into the desired adjusted position. Such movement will shift the rail until it is in holding engagement with the first moved rail clips. In this way, the rail 1 can be 25 adjusted sidewise from the extreme position shown in Fig. 1 to the opposite extreme shown in Fig. 2, or into any position between these extremes. After the rail has been adjusted into the desired position, the 30 nuts 13, 13' are screwed tightly on the bolts so as to firmly clamp the parts in adjusted position and securely hold the rail against sidewise movement.

In the constructions shown in Figs. 4, 5, 35 6, and 8, the rail fastening will be applied in the same manner as has been described above in connection with Figs. 1, 2, and 3.

In the construction of Fig. 7 the sidewise adjustment of the rail will be made in the 40 same manner as in the other figures. In Fig. 7, however, the frusto-conical cam surface on the bolt 10 will frictionally engage with the surface of the conical holes 7 in the rail clips 26, 26' in holding the clips 45 against sidewise movement after the rail has been adjusted and the nuts 13, 13' tightened on the adjusting bolts.

In applying the fastening of Fig. 9, the eccentric washers 33, 33' will be screwed on 50 the bolts 10, 10' until the lower surface of the washers is almost in contact with the rail clip when the rail clips are positioned on the rail support 2 in holding engagement with the rail 1. The nuts 13, 13' will then be 55 screwed on the threaded end 12, 12' of the bolts until they jam on the upper surface of the eccentric washers 33, 33'. The nuts will then be utilized to turn the eccentric washers in moving the rail clips to shift 60 the position of the rail 1 in alining the rail. After the rail has been moved into its adjusted position the nuts 13 and 13' will be held against rotary movement by means of a wrench, while the bolts are turned, by 65 means of the bolt heads, enough to move the

eccentric washers 33, 33' into close engagement with the bottom 35, 35' of the recesses in the upper surface of the rail clips.

The advantages of my invention will be apparent to those skilled in the art. My 70 improved rail fastening enables the track rails to be readily adjusted sidewise in alining and moving the rails to gage, and after tightening the parts in holding engagement will maintain the rails in adjusted position. The wide range of sidewise adjustment afforded by my improved apparatus avoids the necessity of an excessive amount of machine work. The apparatus is simple, 75 is easily and cheaply made, and is readily 80 put into use.

Modifications in the details of construction of my improved rail fastening may be made without departing from my invention as defined in the appended claims. 85

I claim:—

1. In a rail fastening, the combination with a rail support, of a rail clip on said support in holding engagement with the rail base, said support and rail clip having openings therethrough, a fastening bolt extending through said openings, said bolt having an eccentric surface thereon fitting into one of said openings whereby the rail clip and rail are moved sidewise on the rail support 90 when the bolt is rotated, and a nut on said bolt for fastening the parts in adjusted position on the rail support.

2. In a rail fastening, the combination with a rail support, of a rail clip on said 100 support in holding engagement with the rail base, said support and rail clip having a plurality of openings therethrough, fastening bolts extending through the openings in said support and rail clip, said bolts having 105 eccentric surfaces thereon fitting into the openings in the rail clip whereby the rail clip and rail are adjusted sidewise on the rail support when the bolts are rotated, and nuts on said bolts for fastening the parts in 110 adjusted position on the rail support.

3. In a rail fastening, the combination with a rail support, of a rail clip on said support in clamping engagement with the rail base, said support and rail clip having 115 openings therethrough, a fastening bolt extending through said openings, an eccentric washer on said bolt and fitting the opening in said rail clip, said washer being turned when the bolt is rotated to move the rail clip 120 and rail sidewise, and a nut on the bolt for fastening the parts in adjusted position on the rail support.

4. In a rail fastening, the combination with a rail support, of rail clips on said support in clamping engagement with the rail base, said support and rail clips having 125 openings therethrough, fastening bolts extending through said openings, said bolts having eccentric surfaces thereon fitting the 130

4
openings in said rail clips whereby the rail clips and rail are adjusted sidewise on the supporting plate when the bolts are rotated, and nuts on the bolts for fastening the parts in adjusted position on said rail support.

5. In a rail fastening, the combination with a rail support, of rail clips on said support in clamping engagement with the rail base, said support and rail clips having a 10 plurality of openings therethrough, fastening bolts extending through said openings,

an eccentric washer on each of said bolts fitting into an opening in said rail clips, said washers turned by the bolts when the bolts are rotated to thereby move the rail clips and rail sidewise on the rail support, and nuts on said bolts for fastening the parts in adjusted position on said rail support. 15

In witness whereof, I have hereunto signed my name.

FRANCIS LEE CASTLEMAN.
